UNITED STATES PATENT OFFICE.

ALFRED MONARD, OF PARIS, FRANCE.

CONTROLLING RAILWAY POINTS AND SIGNALS.

1,101,563.

Specification of Letters Patent. Patented June 30, 1914.

Application filed November 19, 1912. Serial No. 732,278.

To all whom it may concern:

Be it known that I, ALFRED MONARD, a citizen of the Republic of France, residing in Paris, France, have invented certain new 5 and useful Improvements in Controlling Railway Points and Signals, of which the following is a specification.

The present invention relates to improvements in the construction of the planes or 10 plates constituting the central device for controlling the points and signals of railways, which was described in the Patent Specification No. 568412 of June 22, 1910.

These improvements are described below 15 with the aid of the accompanying drawings, in which—

Figure 1 represents on a small scale the improved plane. Fig. 2 shows a part of Fig. 1 on a larger scale. Figs. 2^a and 2^b 20 are, respectively, sectional views on lines II—II and III—III, Fig. 2. Fig. 3 is a section on the line A—B of Fig. 2. Figs. 4, 5, 6 and 7, 8, 9 show respectively front, side and plan views of the two forms of tappets used in the construction of the planes.

Experience gained in the working of the first central controlling device made has shown that it was necessary to construct the tappets on which the cams of the route 30 keys act, in order to move the planes, so that they practically can never wear out. For this purpose the planes which were formerly cut from a steel sheet, are according to the present invention made of drawn 35 soft steel bars arranged perpendicularly to each other, so as to constitute the frames and by steel tappets of which only the points are made of cement steel and hardened, the whole being riveted together. Bars of four 40 different types are employed in the construction of a plane. The frames are divided vertically by bars *a* to which are secured by rivets *g* bars *b* dividing the frames horizontally and tappets *f* (Figs. 7, 8, 9). 45 The sides of the plane are constituted by vertical bars *c* of *U* section, in which the

bars *b* and tappets *e* (Figs. 4, 5, 6) are secured and by horizontal bars *d* of *T* section securing the double bars *a*. The bars *c* carry threaded bolts *h* for actuating the 50 plane. The heads of the rivets *g* are smoothed over after they have been closed, so as not to project at all beyond the surface of the plane and to cause no impediment to the motion of the plane. 55

Having now described the nature of my said invention and the best means I know of carrying the same into practical effect, I claim:—

1. A frame of the character described, 60 comprising spaced connected vertical and horizontal bars, the bars running in one direction being fixed on either side of the bars running in the other direction, and tappets fixed between the members of the 65 double-bars.

2. A frame of the character described, comprising spaced connected vertical and horizontal bars, the bars running in one direction being fixed on either side of the 70 bars running in the other direction, and tappets fixed between the members of the double-bars, and outside bars of *T* and *U*-sections, the ends of the double-bars being fixed to the bars of *T*-section and the other 75 bars being fixed to the bars of *U*-section.

3. A frame of the character described, comprising spaced connected vertical and horizontal bars, the bars running in one direction being fixed on either side of the 80 bars running in the other direction, and tappets fixed between the members of the double-bars, said tappets having working faces of cement steel.

In witness whereof, I have hereunto 85 signed my name in the presence of two subscribing witnesses.

ALFRED MONARD.
